Herb H. Freeman

INVENTOR.

UNITED STATES PATENT OFFICE

2,329,261

PENDULOUS FENCE PANEL

Herbert H. Freeman, Minneapolis, Minn.

Application July 14, 1943, Serial No. 494,701

1 Claim. (Cl. 256—65)

My invention relates to an improvement in the suspending mechanism for pendulous fence panels.

The object of my invention is: to provide a bearing-plate bolted or otherwise secured to the under surface of the top panel-rail and having its outer, or post end, bent downward and perforated to engage and encircle the suspending lug in the adjacent post, and its inner or panel end also bent downward to prevent the lug in 10 the post being driven out of the said post.

In the drawing Fig. 1 is a layout or plan of the bearing plate 1, before its ends are bent on the dotted lines, shown at 9 and 10, and assuming the position shown in Fig. 2 at 3 and 4. Holes 15 5, 5' are for bolts or screws securing plate to top

5 rail. The hole or perforation 2, in Fig. 1, receives the lug in the adjacent fence post. In Fig. 2 the top rail 6 of the panel, the post 7 and the lug 8, are shown in dotted outline only so that the bearing-plate 1 with the legs 3 and 4 may be more clearly delineated.

What I claim is:

In combination, in a pendulous fence panel suspended from lugs or pins affixed to adjacent posts, a bearing-plate affixed to the top rail of said panel and having its outer or post end bent and perforated to encircle the adjacent post lug, and its inner or panel end also bent to prevent lugs being driven from post.

HERBERT H. FREEMAN.
